United States Patent Office.

HENRY R. HALL, OF PHILADELPHIA, PENNSYLVANIA.

Letters Patent No. 77,187, dated April 28, 1868.

ENAMELLING-MACHINE.

The Schedule referred to in these Letters Patent and making part of the same.

TO ALL WHOM IT MAY CONCERN:

Be it known that I, HENRY R. HALL, of Philadelphia, Pennsylvania, have invented certain new and useful Improvements in Enamelling-Machinery; and I do hereby declare that the following is a full and exact description of the same; reference being had to the annexed drawings, and to the letters of reference marked thereon, in which drawings—

Figure 1 is a perspective view of the machine, one corner being broken away to disclose the under gearing, a part of which appears in red lines.

Figure 2 is a vertical section on the line $y y$ of fig. 1, the endless chain being removed to show the bed-plates.

Figure 3 is a perspective view of a part of the machine, showing a piece of moulding as it passes, by the action of the endless chains, through the scrapers, and showing also the springs by which the scrapers are enabled to adjust themselves to the mouldings.

Figure 4 is a similar view of the guides or ways, against which the endless chains have a lateral bearing.

Figure 5 is a similar view of a portion of the endless chain, showing its flat links.

Figure 6 is a similar view of the pinion-wheel.

Figure 7 is a vertical section of the pulley and of part of the stud upon which it turns.

In fig. 1, a represents the table by which the machine is supported. $b b^1 b^2$, figs. 1 and 2, are three separate bed-plates, the middle plate, b^1 , being fixed to the table, and the plates b and b^2 being movable to or from the fixed plate b^1 , to adjust the machinery to various sizes of the mouldings or other things to be enamelled. $c c^1 c^2$ are pulleys, turning respectively upon upright studs, $d d^1 d^2$, which project from the bed-plates $b b^1 b^2$. $e e^1 e^2$ are pinion-wheels, fastened respectively to the upright shafts $f f^1 f^2$, which have fastened on their lower ends the bevel-cog wheels $g g^1 g^2$, which gear into the similar wheels, $h h^1 h^2$, on the driving-shaft i , which is provided with feathers, j , which enter corresponding recesses in the wheels $h h^2$. The wheels $h h^2$ are further secured, and wheel h^1 is also secured to the shaft i by set-screws, as shown. By removing their set-screws, the wheels $h h^2$ may be adjusted on the shaft i , to correspond with any adjustment of the bed-plates $b b^1 b^2$, and parts attached. $k k^1 k^2$ are endless chains, passing edgewise around pulleys $c c^1 c^2$ and pinion-wheels $e e^1 e^2$, respectively, having flat links, as shown, to feed forward the mouldings, and at the same time save them from indentations, and having lateral support against the guides or ways $m m'$, figs. 1 and 4. The two plates, which constitute the ways $m m'$, are rigidly attached by studs to the bed-plates $b b^1 b^2$ respectively. The middle and larger portions of the sides of the ways $m m'$ are parallel, and the ends of said ways are rounded off, as shown, to allow the chains to be turned with more ease, and without indenting the mouldings or other things being enamelled. $n n'$ are thumb-screws, (abutting against springs v), by which the movable plates, $b b^2$, and their respective chains, are set further from or nearer to the fixed plate b^1 and chain k^1 , to suit the various sizes of mouldings, &c. o , figs. 1 and 3, is a hopper, such as is now generally employed in enamelling. The scrapers $w w'$ constitute the ends of hopper o .

I secure the hopper o to the table a by means of springs p , fig. 3. A similar hopper is placed at q , fig. 1.

Power is applied to the driving-shaft i . The pinion-wheels $e e^1 e^2$, being thus put in motion, give motion to the endless chains. The ends of the mouldings, u , fig. 3, or other things intended to be enamelled, are introduced at r to the space between chains k and k^1 , and at s to the space between chains k^1 and k^2 , and are fed forward through the scrapers $w w'$.

It is obvious that there are various arrangements of springs, other than the arrangement shown, by which the hoppers and scrapers may be made self-adjustable to the form of the mouldings.

It is also obvious that the chain-guides or ways $m m'$, instead of being composed of two plates united by studs, as shown, might be cast in a solid piece, with its edges grooved out sufficiently to prevent interference with the chains; or these ways might be composed of bars, attached to the bed-plates in any convenient manner, the edges or faces of the bars presenting lines similar to the lines of the edges of plates $m m'$.

Instead of employing the three endless chains $k k^1 k^2$, two only, as $k k^1$, may be employed, if desired, or

the number of chains may be increased indefinitely, the supporting-table *a* being enlarged, and the necessary running-gear, similar to that described, being correspondingly supplied.

Instead of attaching the scrapers to the table by means of springs, as shown, they might be rigidly fastened to the table, or they might be entirely separate from the table, and applied to the mouldings by the hands of an operator, or a single separate scraper might be thus applied.

Having thus described my invention, I claim, and desire to secure by Letters Patent—

1. Making the hoppers and scrapers self-adjustable by the application of springs shown and described.
2. Feeding the mouldings or other objects to be enamelled through the scrapers by means of endless chains set edgewise, and provided with flat links to prevent indentation of the mouldings, substantially as shown and described.
3. Making the bed-plates *b* and *b*², both or either of them, with their chains or other attached parts, adjustable relatively with the fixed bed-plate *b*¹, its chain and other attached parts, to adapt the machine to the various sizes of mouldings or other objects to be enamelled, substantially as shown and described.
4. The endless chains *k* *k*¹, their respective ways or lateral bearings *m* *m*¹, and the mechanism for giving motion to said chains, in combination with two scrapers or a single scraper, substantially as shown and described, for the purpose specified.

HENRY R. HALL.
